DESIGN FOR A HOLDER FOR EDIBLE ARTICLES OF FOOD AND CONFECTIONS

Winifred Rohrs and Lynton Wright Brent, Los Angeles, Calif.

Application June 6, 1933. Serial No. 48,300

Term of patent 3½ years

To all whom it may concern:

Be it known that we, WINIFRED ROHRS and LYNTON WRIGHT BRENT, citizens of the United States, residing at Los Angeles, in the county of Los Angeles and State of California, have invented a new, original, and ornamental Design for a Holder for Edible Articles of Food and Confections, of which the following is a specification, reference being had to the accompanying drawing, forming part thereof.

We claim:

The ornamental design for a holder for edible articles of food and confections, as shown.

WINIFRED ROHRS.
LYNTON WRIGHT BRENT.
